1 Claim. (Cl. 221—147)

This invention pertains, in general, to the dispensing of lighted cigarettes; and, in particular, to new and improved electrical circuitry for lighting cigarettes to be dispensed by a dispensing machine. The electrical circuitry provided by the present invention is an improvement over the electrical cigarette-lighting circuitry disclosed in the United States Patent No. 2,936,930 for "Cigarette Dispenser With Electric Lighting Device," granted on May 17, 1960.

In the cigarette dispenser according to Patent No. 2,936,930, a conveying mechanism transfers cigarettes, individually, from a cigarette magazine to an electrically heated lighting device. After the cigarette has been lighted, the conveying mechanism transfers the lighted cigarette to an opening in a housing of the cigarette dispenser so that the smoker can take the cigarette and smoke it. In order to light the cigarette, the conveying mechanism moves the cigarette so that one end of the cigarette abuts against a resistance wire heater element. The resistance wire heater element is arranged in a series circuit with a pair of spring contacts which comprise a normally-open switch; the normally open switch and resistance wire heater element being connected across a voltage source, such as a battery. When the end of the cigarette is placed in abutment with the resistance wire heater element, a pin on a moving control rod engages a cam piece which is fixed to one contact of the spring contact pair and causes the spring contacts to close for a short duration of time, thereby allowing current from the voltage source to heat the resistance wire heater element to light the end of the cigarette.

Experience with the above-described cigarette dispenser has demonstrated that a great deal of care and expense is required in making and assembling the control rod, pin, cam piece and spring contacts. For example, the sizing and contouring of the cam piece and its arrangement with respect to the control rod's pin requires a great deal of precision. Otherwise the cigarette lighting operation will not always be carried out properly. In addition, it has been found that a great deal of care is required in arranging the spring contacts in relation to the control rod's pin in order to maintain low contact resistance. This is particularly critical when the resistance wire heater element draws 12 to 15 amperes from voltage sources of 6 to 12 volts.

Accordingly, one object of the present invention is to provide a cigarette lighting circuit for a cigarette dispenser which obviates the aforementioned disadvantages.

Another object of the present invention is to provide a new and improved cigarette lighting circuit adaptable of being incorporated in cigarette dispensers of the kind hereinbefore described.

Another object of the present invention is to provide a cigarette lighting circuit which is relatively simple, highly reliable and relatively inexpensive.

According to one embodiment of the present invention, there is provided a relay including a coil and a set of normally-open contact elements which close when the coil is energized. The normally-open relay contact elements are connected in series with a resistance wire heater element; the heater element and relay contact elements being connected across a voltage source. Also

2

connected across the voltage source and in parallel with the series-connected relay contact elements and heater element are the serially connected relay coil and two sets of normally-open spring contact elements.

The circuitry hereinbefore described is incorporated into the cigarette dispenser disclosed in Patent 2,936,930. As may be understood by referring to that patent, and from the detailed description hereinafter, as a result of manually actuating a push button 2, a control rod 32 having a pin 31 attached thereto is moved longitudinally in a forward direction. In addition, a plate-like slider 9 associated with a cigarette magazine chamber 1 moves laterally to move one cigarette into a conveying mechanism. The circuitry of the present invention is incorporated into the cigarette dispenser of Patent 2,936,930 so that the following occurs:

As the control rod 32 moves longitudinally in a forward direction, a second pin on the control rod moves forward and one of the two sets of spring contact elements in series with the relay coil is closed. Subsequently, and immediately before the cigarette, being carried by the conveying mechanism, is brought into abutment with the resistance wire heater element, the other set of spring contacts, in series with the relay coil, is closed by the laterally moving slider 9. As a consequence, the relay coil is energized and the relay contact elements are closed, thereby allowing current from the voltage source to pass through the heater element and heat the heater element whereby the arriving cigarette end is lighted. Subsequently the control rod 32, by virtue of the action described in Patent 2,936,930 and hereinafter, moves longitudinally in a reverse direction. Eventually the second pin on the moving control rod 32 again engages one of the sets of spring contacts and opens them. Thus, the relay coil is deenergized and the relay contact elements return to their normally open condition and current flow to heater element is discontinued. Also, the slider 9 returns laterally in the opposite direction to open the other of the sets of contact elements so that both sets of contact elements in series with the relay coil are opened.

The various features of novelty which characterize the invention are pointed out with particularity in the claims annexed to and forming a part of this specification. For a better understanding of the invention, its operating advantages and specific objects attained by its use, reference should be had to the accompanying drawing and descriptive matter in which there are illustrated and described preferred embodiments of the invention.

50 In the drawing:

FIG. 1 is an elevation view, partly cut away for purposes of clarity, showing the arrangement of elements of the present invention as incorporated into a cigarette dispenser of the type disclosed in U.S. Patent 2,936,930;

55 FIG. 2 is a schematic diagram of the cigarette-lighting electrical circuitry according to the present invention;

FIG. 3 is a front view of the frontal portion of the cigarette dispenser, partly in section and with the front wall being removed;

60 FIG. 4 is a front view similar to that of FIG. 3, but showing the first stage of operation, namely a cigarette being just in position to be lighted;

FIG. 5 is a top plan view of the dispenser, the cover plate of the housing as well as the bottom plates of the magazine chamber being removed;

FIG. 6 is a top plan view of the center portion of the dispenser at the height of the pusher rods;

FIG. 7 is an end view partly in section;

70 FIG. 8 is a top plan view of the dispenser shown in FIG. 7, some parts being removed; and

FIGS. 9 and 10 are fragmentary views of the dispenser disclosing particularly the latch of the pusher rod.

FIGS. 3, 4, 5, 6, 7, 8, 9 and 10 correspond, respectively, to FIGS. 1, 3, 2, 4, 5, 6, 7 and 8 of said Patent No. 2,936,930, being modified to illustrate the improvement of the present invention.

For convenience, elements common to the subject matter of the present invention and those of U.S. Patent 2,936,930 bear the same reference number designations. It is believed that a better understanding of the invention will be obtained if reference is made first to FIGS. 3-10 showing, principally, the construction of the dispenser of U.S. Patent No. 2,936,930.

Referring to FIGS. 3-10, the illustrated dispenser has a magazine chamber 1 and is provided with a push button 2 (FIGS. 5, 6 and 7) which is disposed normally outside of a housing G, but which may be pushed into housing G, by manual operation, through an opening of the housing. Push button 2 is mounted on a pusher rod 3 and has a lateral groove 2a into which the end of a control rod 32 may enter during a predetermined phase of the operation of a dispenser.

Pusher rod 3 carries a lateral pin 10 (FIG. 6) which engages a recess in an angular lever 11 and turns this lever clockwise about a pivot pin 20 when rod 3 is pushed by operation of button 2. Angular lever 11 has a short arm with a lateral lug 11a, and a long arm with a rounded nose 12. Nose 12 is adapted to engage the face 13 of a slider 9 as best seen in FIGS. 3 and 8. Slider 9 then moves from the left toward the right horizontally, as viewed in FIG. 3, beneath the hinged bottom plates 50 and 51 of magazine chamber 1. Slider 9 has bent-off side portions and is formed with slots 16, as best seen in FIGS. 3 and 4, which receive guide bolts 48 (FIGS. 5 and 8) and which also connect the side walls 17, 18 of magazine chamber 1 within housing G. A downwardly extending lug 25 of slider 9 (FIG. 3) forms, together with the likewise downwardly extending edge portion of an inclined closure plate 15, a trough 25'. The bottom of trough 25' is formed by a fixed sheet member 19, the pivot pin 20 of angular lever 11 being fastened to the downwardly extending portion 21 of sheet member 19. In trough 25' is disposed a lowermost cigarette Z of the cigarette supply in the magazine chamber 1 before the dispenser is put in operation.

Bottom plates 50 and 51 of magazine chamber 1 are movable up and down in mutually opposite directions, as will be more fully described. This reciprocating motion of the bottom plates serves the purpose of preventing mutual bracing or edging of the cigarettes in the magazine chamber 1, thus assuring a reliable discharge of only a single cigarette at a time. When rod 3 is pushed, by depression of push button 2, slider 9 moves toward the right, as viewed in FIGS. 3 and 4, and toward the left, as viewed in FIG. 8, until its portion 21 abuts against and is latched a pawl 14 pivoted at 14a (FIG. 8). Displacement of slider 9 entrains also closure sheet 15, as seen in FIG. 4, which lifts bottom plate 50 of magazine chamber 1 and closes the gap between the two bottom plates 50 and 51 while shoving the single cigarette Z, on sheet 19, toward the right (FIG. 4). At the same time, a recessed portion 46 (FIG. 8) of slider 9 pushes against an angular member 52 pivotally connected with bottom plate 51. This turns member 52 about its pivot in opposition to the force of a spring 53 (FIG. 3) so that bottom plate 51 is forced downwardly as seen in FIG. 4. Movement of plate 51 is limited, in both directions, by means of a guiding slot 54 and a guide pin 44 near the front edge of bottom plate 51.

The upwardly rotating bottom plate 50 and the downwardly rotating bottom plate 51 cooperate to move the cigarettes in magazine chamber 1 against each other to preserve the necessary mobility of the individual cigarettes so that edging and clogging of the cigarette supply is prevented.

The single cigarette Z displaced from sheet member 9 transversely to the cigarette axis drops into a holding

claw 4 (FIGS. 3 and 4). At that particular instant, a pivoted and spring biased member 4a of claw 4 is held open by lug portion 25 of slider 9 which is moving or pushing toward the right, as viewed in FIGS. 3 and 4. Claw 4 has a bottom piece 26 guided in a longitudinal slot 27 of a trough 28 which, aside from forming a guide for claw 4, also serves to prevent edging of the cigarette when dropping into the claw.

A head 26a is connected with claw bottom piece 26 and glides in a guiding slot 24a of a lever 24 (FIGS. 5 and 6) pivoted at 24b. Lever 24 is rotatable from the full line position of FIG. 5 to the broken line position thereof and, during such rotation, moves claw 4 in longitudinal slot 27 from the front to the rear of trough structure 28. Lever 24 is driven by a cross pin 22 of pusher rod 3, this cross pin being engaged in an elongated slot or opening 23 of lever 24.

At the moment when the single cigarette Z drops into holder claw 4, lever 24 has swung forwardly into approximately one-half of its angular displacement between its limiting positions. At the same moment, spring biased member 4a of claw 4 slides off lug portion 25 of slider 9 and thus clamps cigarette Z in the claw so that the cigarette, during the further forward travel of lever 24 and claw 4, is displaced longitudinally toward lighter 5.

All these constrainedly controlled motions take place during inward movement of pusher rod 3. At the same time, pusher rod 3 causes a charging of power storing devices consisting of the tension springs 6, 7 and 8 shown in FIGS. 3, 4, 5, 6 and 8. These springs, thus tensioned, individually actuate the return motion of the pusher and control rods and the return of the control slider 9. Suitable means are provided for securing uniform inward and outward motion of pusher rod 3 during its forward and return runs. As shown in FIGS. 5, 6, 7 and 8, this means may comprise the piston 36 of an air brake cylinder 40, which piston is mounted on the inward end of pusher rod 3 as best seen in FIGS. 5 and 6. Alternatively, such uniform operation may be obtained by the arrangement shown in FIG. 1, which comprises a bellows 95 which is connected to push rod 3.

As best seen in FIGS. 7, 9 and 10, two latch pawls 29 and 30 are pivotally linked to pusher rod 3 as by being mounted on a common pivot pin 58. Pawl 29 has a recess 29a (FIG. 7) which catches onto a fixed angular bearing piece 45 and thus latches pusher rod 3 in its rear or inward limiting position. Recess 29a is located at the end of a slanting edge surface 29b whose purpose will be explained further hereinafter. As best seen in FIGS. 9 and 10, pawl 30 has two pointed tips 30a and 30b. During inward displacement of pusher rod 3, tip 30a abuts against a pin 31 of a control rod 32 which extends and is displaceable in parallel relation to pusher rod 3. Near the end of the forward or inward displacement of pusher rod 3, tip 30b of pawl 30 glides onto the upper edge of the rear bearing angle 45, as seen in FIG. 10. This causes lifting of pawl 30 so that pin 31 is released and control rod 32 commences its return motion under the pull of spring 6. This action occurs immediately after latching of pusher rod 3 in the inward limiting position.

Heater spiral 5 is designed and shaped in accordance with well-known cigar and cigarette lighters. During the forward or inward run of pusher rod 3, cigarette Z has its end placed against heater spiral 5 due to the action of lever 24 and claw 4 driven thereby. Hence, cigarette Z is lit as soon as the electric heating current is switched on as will be described hereinafter.

Control rod 2 is also provided with a braking device for securing a slow, uniform and controllable return travel. For this purpose, a rack 33 is attached to control rod 32 (FIG. 7) and meshes with a pinion 34 (FIG. 4) for driving eddy-current brake 35 (FIG. 7). The mechanism is provided with a free-wheeling clutch (not shown) so that eddy-current brake 35 operates only during return travel of control rod 32. Since such eddy-current brakes

are generally known and their structural details are not part of the invention proper, the brake is not further described herein. In lieu of an eddy-current brake, other known adjustable braking devices, such as liquid brakes, centrifugal speed regulators, and the like, may be used in combination with an overrun or free-wheeling clutch.

A releasing plate 39 (FIG. 7) is located at the inward end of control rod 32. After lighter 5 is deenergized in a manner to be described, by return movement of control rod 32, releasing plate 39 is engaged by the inclined edge 29b of pawl 29 so that the latter is lifted. As a result, pusher rod 3 is unlatched from rear bearing angle 45 and commences its return run under the action of tension spring 7. At the starting moment of this run, pin 22 in elongated hole 23 of lever 24 acts to displace holder claw 4 together with the lit cigarette Z in the trough 28 in the outward direction until lever 24 again reaches the full line starting position of FIGS. 5 and 6. In this position, the tip of cigarette Z protrudes through the front wall of the dispenser housing so that the cigarette can be removed readily. At the same time, guide pin 10 returns angular lever 11 so that lug 11a of the short lever arm releases latch 14 of slider 9. The slider 9 is thus returned to its starting position by the action of tension spring 8. The aforementioned braking means provide for a uniform and slow return movement of pusher rod 3 back to its starting position.

The cigarette dispenser is further provided with a latching device which prevents repeated operation of pusher rod 3 before the lit cigarette is removed. For this purpose, a pawl 42 is pivotally mounted on the front bearing angle 43 of pusher rod 3. Pawl 42 is latchingly engageable with a recess 41 of pusher rod 3 in order to prevent renewed operation of the rod. Pawl 42 is loosely connected with a rod 44 disposed and guided in a groove of trough 28. When the lit cigarette is removed from the dispenser, resilient claw 4a closes and presses against rod 44, thus shoving pawl 42 out of groove 41 in pusher rod 3. As a result, the latching of the pusher rod in its outward, inactive position is released as soon as the lit cigarette is taken from the dispenser. Thereby, a push button 2 can be depressed again for lighting and dispensing another cigarette.

As illustrated at FIG. 1, a relay comprising a relay coil 82 and a set of associated contacts 80 and 81 is mounted on housing G of the cigarette dispenser. Within the housing G there is situated, as described laterally moveable slider 9 and longitudinally movable control rod 32, having pin 31 and a second pin 31a fastened thereto. Within the housing G and protruding therethrough is pusher rod 3 which is longitudinally movable by manual actuation of push button 2 associated therewith.

Also situated within the housing G are the spring contact elements 83, 84 and 85. Spring contact elements 83 and 84 form part of a switch assembly which is mounted on the left-hand wall of housing G, as viewed from the operating end of the dispenser. Switch assembly 85, as best seen in FIG. 8, is mounted on the right-hand wall of housing G, which is the wall approached by slider 9 when the latter is displaced by operation of push button 2 as already described. In the condition shown at FIG. 1, the cigarette dispenser is in its non-operated status such that the control pin 31a flexes the spring contact 83 away from the spring contact 84, thus maintaining an open circuit condition therebetween. Also, in the non-operated status of the dispenser shown in FIG. 1, the slider 9 has its retracted position in which the spring contacts 85 are in an open condition.

As illustrated at FIG. 2, wherein the normal or non-operated status of the cigarette-lighting circuitry is shown, the connection terminals 91, 91 of the subject circuitry are connected across a voltage source (not shown) through a suitable fuse 90. One of the terminals 91 is, as shown, connected to ground 92. The relay contacts 80 and 81

which are adapted to be closed upon energization of the relay coil 82, are connected in series with a resistance wire heater element 5 across the voltage source. Connected in parallel across the heater element 5 is an indicator lamp 37 which is mounted on the front wall of the housing G. As shown, another series circuit is connected in parallel across the relay contacts 80, 81 and the heater element 5. This other series circuit is comprised of the serially connected contacts 83, 84, 85 and the relay coil 82.

In accordance with the orientation shown in FIG. 1, as the pusher rod 3 is moved toward the left, the control rod 32 with its pin 31a also moves toward the left. As pin 31a moves toward the left, the spring contact 83, by virtue of its spring bias, will move into contact with the spring contact 84. Subsequently, and immediately prior to the arrival of the cigarette into abutment with the heater element 5, the spring contact set 85 is closed by virtue of the aforementioned lateral movement of slider 9. Closure of contacts 85 is effected by suitable means 96 positioned on slider 9 and engageable with contacts 85 when slider 9 moves to the left as viewed in FIG. 8. Since the contact 83 is closed with contact 84 and the contact elements 85 are closed, there is completed a series circuit with the relay coil 82 and the voltage source, thereby energizing relay coil 82. Upon energization of the relay coil 82, contact element 80 moves into contact with the contact element 81. As a consequence there is completed a series circuit between the relay contacts 80, 81 and the heater element 5 with the voltage source, allowing the heater element 5 to generate enough heat to light the end of the cigarette. Subsequently the control rod 32 and the pusher rod 3 are uncoupled, in the manner described, whereupon the control rod 32 moves longitudinally toward the right (according to the orientation of FIG. 1) toward its starting position. Eventually, the pin 31a reengages the spring contact 83 and moves it out of engagement with the contact 84, thereby disrupting the flow of current through the relay coil 82. Also slider element 9 returns to its starting position in the manner described. Upon returning, slider 9 opens the set of contacts 85, whereby all of the contacts in series with the relay coil 82 are opened. When control pin 31a disengages contact element 83 from contact element 84, the relay contacts 80, 81 are opened, thereby interrupting the flow of current to the heater element.

While a specific embodiment of the invention has been shown and described in detail to illustrate the application of the inventive principles, it will be understood that the invention may be embodied otherwise without departing from such principles.

The embodiments of the invention in which an exclusive property or privilege is claimed are defined as follows:

A cigarette dispenser comprising, in combination, a housing having a dispensing opening; an electric lighting device mounted on said housing and coaxially spaced from said opening; a cigarette magazine in said housing, said magazine having two bottom plates forming together an elongated gap through which an individual cigarette may pass; conveying mechanism in said housing, and including slider means and cigarette-holding claw means; said slider means being displaceable, from a starting position to an operating position, in a direction transverse to said gap for shifting said individual cigarette into said claw means; a trough structure extending beneath said claw means from said lighting device to said dispensing opening, said claw means being displaceable in and along said trough structure for longitudinally displacing said individual cigarette into lighting contact with said lighting device and thereafter in the reverse direction and partly out of said dispensing opening; a pusher rod having a starting position and being manually controllable to move longitudinally inwardly from said position; said claw means having a starting position and said slider means and said claw means being coupled with said pusher rod and entrainable thereby during inward movement of said pusher rod; a plurality of spring means connected with

said slider means and claw means, said pusher rod, and said control rod for tensioning by inward movement of said pusher rod for individually returning said pusher rod, said control rod and said slider means and claw means to their respective starting positions; plural releasable latch means operable to releasably maintain said pusher rod and said slider means in the operated positions thereof; releasing means for disengaging said control rod from said pusher rod at the end of the inward run of said pusher rod for return of said control rod by one of said spring means; means operable, responsive to return of said pusher rod to its starting position, to release the latch means of said pusher rod for return of said pusher rod to its starting position; means operable, responsive to return movement of said pusher rod, to release the latch means for said slider means for return of said slider means to its starting position by one of said spring means; a first normally open switch mounted on a wall of said housing; means carried by said control rod and engageable with said first switch, upon the start of movement of said control rod inwardly from its starting position, to close said first switch and to maintain said first switch closed until return of said control rod to its starting position; a second normally open switch mounted on a wall of said housing; means on said slider means engageable with said second normally open switch to close the latter when said slider means reaches

its operating position; a relay mounted on said housing and including an operating coil and a set of relay contacts which are closed responsive to energization of said operating coil; means connecting said relay contacts in series with said lighting device and a voltage source; and a series circuit including said first and second switches; said relay operating coil, and the voltage source; whereby said relay coil is energized upon conjoint closure of said first switch means, responsive to movement of said control rod from its starting position, and said second switch, responsive to movement of said slider means to its operating position, so that said electric lighting device is energized only when said control rod has been entrained by said pusher rod during inward movement of the latter and when said slider means has reached its operating position to move a cigarette into said claw means.
